UNITED STATES PATENT OFFICE.

SAMUEL MOSES, OF JERSEYVILLE, ILLINOIS.

FLYING-MACHINE.

1,287,076.

Specification of Letters Patent. Patented Dec. 10, 1918.

Application filed May 20, 1918. Serial No. 235,656.

To all whom it may concern:

Be it known that I, SAMUEL MOSES, a citizen of the United States, residing at Jerseyville, in the county of Jersey and State of Illinois, have invented new and useful Improvements in Flying-Machines, of which the following is a specification.

This invention relates to flying machines of the heavier than air type, the object in view being to provide a specially safe and efficient air craft embodying a novel arrangement of fuselage supporting surfaces and lifting and propelling means, whereby the machine may be launched into actual flight in a circumscribed field or space, and whereby also a safe landing may be effected in a correspondingly small area. The machine has great lifting and carrying capacity particularly adapting the same for military and war purposes, as well as the carrying of a large number of passengers and a large quantity of freight.

With the above and other objects in view, the invention consists in the construction, combination and arrangement of parts, as herein described, illustrated and claimed.

Figure 1 is a plan view of the improved flying machine.

Fig. 2 is a horizontal section thereof showing the propeller actuating connections.

Fig. 3 is a front elevation of the machine.

Fig. 4 is a vertical longitudinal section through the fuselage.

Fig. 5 is a vertical transverse section taken in line with the rear lifting propeller shafts.

Fig. 6 is a fragmentary vertical longitudinal section showing the gearing and clutch mechanism for throwing the lifting and driving propellers alternately into and out of gear.

In carrying out the present invention, I employ a fuselage 1 of sufficient size to carry and inclose practically all the mechanism of the machine. The fuselage is of a general rectangular shape in plan as well as side elevation but the forward end thereof is pointed to form a prow or stem 2 enabling the fuselage to cleave the air with reduced head resistance.

Arranged adjacent to each of the four corners of the fuselage and extending vertically through the same from top to bottom is an upright tubular housing or air well or conduit 3 and above the upper end of each tubular conduit is arranged a lifting propeller 4 which turns on a vertical axis, said propeller

being fastened to the upper section 5 of a vertical propeller shaft, said upper section of the shaft being shown as tubular. The shaft also comprises a main section 6 which fits telescopically within the upper section 5. The shaft section 6 is connected by bevel gears 7 to transversely extending shaft 8 which is in turn connected by gears 9 to a longitudinal shaft 10, the latter being coupled to and driven by the shaft of an engine 11, located about centrally of and within the fuselage.

Mounted fast upon each shaft section 6 is a beveled gear 12 having a clutch 13 for engagement with a clutch 13' shiftable by means of a lever 14, said clutch being keyed to and slideable upon the tubular shaft section 5. This provides means for throwing the respective lifting propeller into and out of operation. Each gear 12 meshes with and drives another beveled gear 15 loose on a horizontal shaft 16 having secured to the rear end thereof one of a pair of driving propellers 17. The gear 15 is normally loose on the shaft 16 but is adapted to be thrown into engagement therewith so as to rotate the shaft 16 by means of a slideable clutch 18 shifted by means of a lever 18'. The levers 18' are mounted upon rock shafts 19 having arms 19'. The clutch shifting levers 14 are also mounted upon rock shafts 21 each having an arm 21' connected by a rod 22. A rod 23 extends from one lever 21' to a manually operable lever 23' arranged adjacent to the aviator's seat as shown in Fig. 4. Another rod 23' extends from the other arm 19' to another manually operable lever 22' adjacent to the aviator's seat. It will thus be seen that the lifting propellers 4 and the driving propellers 17 may be alternately thrown into and out of operation, the lifting propellers being used until the desired altitude has been obtained, after which the driving propellers are thrown into operation, and the lifting propellers are thrown out of operation, the machine being then supported by the laterally extending lifting and supporting surfaces or wings 24 which extend from opposite sides of the fuselage 1.

The fuselage is entirely covered or sheathed with any suitable material, such as fabric, properly treated to render the same water, air and fire proof, the only openings therein being at the top and bottom of the wells or conduits 3, so that the lifting propellers 4 may drive the air downwardly there-

through. This enables the machine to float when a landing is made on water. Windows may, of course, be arranged at any desired points in the fuselage, the same being covered by transparent panels. Arranged above the top wall of the fuselage and adjacent to the forward end thereof is a vertical rudder 25 which is flexibly connected at its forward edge to a vertical rudder post or shaft 10 26, extending downwardly into the fuselage where it is connected by gears 27 to a steering shaft 28 having one or more knuckle points 29 therein. The rear section of the shaft 28 has a hand control or steering wheel 29' fast thereon and arranged conveniently with respect to the aviator's seat. The lifting propellers 4 are geared so that oppositely located propellers revolve simultaneously in opposite directions, one to the right and one to the left, thus equalizing the gyroscopic action of said lifting propellers and adding to the factor of safety of the machine. The driving propellers 17 are also geared so as to be driven simultaneously 25 in opposite directions, one to the right and one to the left.

From the foregoing description, taken in connection with the accompanying drawings, it will now be seen that I employ two sets of propellers, one set for direct lifting and another set for propelling the machine in a forward direction. These two sets of propellers are designed to be operated alternately, the lifting propellers for ascending 30 and descending and the driving propellers 35 18 mainly for propelling the machine in a forward direction, although it will be apparent that the propellers 18 may be used also for ascending and descending or in the 40 same manner as the propelling mechanism of an ordinary airplane, the wings 24 forming necessary aerial support for the machine. The lifting propellers 4 are used mainly for 45 ascending and descending where there is only a sectional ground area available and they are also used for obtaining a high altitude more quickly than would be possible with the driving propellers 8 alone. Any suitable means may be provided for maintaining the 50 lateral equilibrium of the machine, such as the usual lateral balancing surfaces.

I claim:

1. In a flying machine, the combination of a closed fuselage, laterally extending aerial 55 supporting surfaces projecting from oppo-

site sides thereof, tubular air conduits extending from top to bottom of said fuselage and open at both ends, lifting propellers rotatable in the upper ends of said conduits, vertical shafts for said lifting propellers housed within said conduits, driving propellers arranged at one end of the fuselage, shafts for the last named propellers, gearing for driving said lifting and pushing propellers, and manually controlled means for throwing the lifting and pushing propellers alternately into and out of operation.

2. In a flying machine, the combination of a closed fuselage, laterally extending aerial supporting surfaces projecting from opposite sides thereof, tubular air conduits extending from top to bottom of said fuselage and open at both ends, lifting propellers rotatable in the upper ends of said conduits, vertical shafts for said lifting propellers housed within said conduits, driving propellers arranged at one end of the fuselage, shafts for the last named propellers, gearing for driving said lifting and pushing propellers manually controlled means for throwing the lifting and pushing propellers alternately into and out of operation, said fuselage being of substantially rectangular formation in plan, and said lifting propellers and conduits being located adjacent to the corners of the fuselage.

3. In a flying machine, the combination of a closed fuselage, laterally extending aerial supporting surfaces projecting from opposite sides thereof, tubular air conduits extending from top to bottom of said fuselage and open at both ends, lifting propellers rotatable in the upper ends of said conduits, vertical shafts for said lifting propellers housed within said conduits, driving propellers arranged at one end of the fuselage, shafts for the last named propellers, gearing for driving said lifting and pushing propellers, manually controlled means for throwing the lifting and pushing propellers alternately into and out of operation, a vertical rudder mounted above the top of the fuselage, a rudder post journaled to turn on a vertical axis at the center of the forward end of the fuselage, and a manually controlled steering shaft geared to said rudder post.

In testimony whereof I affix my signature.

SAMUEL MOSES.
